CLAIM

The ornamental design for a fuse, as shown and described.

DESCRIPTION

FIG. 1 is a perspective view of my new design; FIG. 2 is a front elevational view of the new design; FIG. 3 is a side elevational view of the new design; FIG. 4 is a bottom plan view of the new design; and FIG. 5 is a top plan view of the unclaimed top surface of the fuse.

The broken line showing of a cap element and prongs is for illustrative purposes only and forms no part of the claimed design.
